(57) **CLAIM**

The ornamental design for a bottle with dispensing cap, as shown and described.

DESCRIPTION

FIG. 1 is a perspective view of a first embodiment of a bottle with dispensing cap taken from above;

FIG. 2 is a perspective view of a first embodiment of a bottle with dispensing cap taken from the bottom;

FIG. 3 is a right-side view of the bottle with dispensing cap of FIG. 1;

FIG. 4 is a frontal view of the bottle with dispensing cap of FIG. 1;

FIG. 5 is a left-side view of the bottle with dispensing cap of FIG. 1;

FIG. 6 is a rear view of the bottle with dispensing cap of FIG. 1;

FIG. 7 is a top view of the bottle with dispensing cap of FIG. 1;

FIG. 8 is a bottom view of the bottle with dispensing cap of FIG. 1.

FIG. 9 is a perspective view of a second embodiment of a bottle with dispensing cap taken from above;

FIG. 10 is a perspective view of a second embodiment of a bottle with dispensing cap taken from the bottom;

FIG. 11 is a right-side view of the bottle with dispensing cap of FIG. 9;

FIG. 12 is a frontal view of the bottle with dispensing cap of FIG. 9;

FIG. 13 is a left-side view of the bottle with dispensing cap of FIG. 9;

FIG. 14 is a rear view of the bottle with dispensing cap of FIG. 9;

FIG. 15 is a top view of the bottle with dispensing cap of FIG. 9; and,

FIG. 16 is a bottom view of the bottle with dispensing cap of FIG. 9.
